UNITED STATES PATENT OFFICE.

JAMES F. DUNN, OF SALT LAKE CITY, UTAH.

RAILWAY-CAR.

SPECIFICATION forming part of Letters Patent No. 634,749, dated October 10, 1899.

Application filed April 4, 1899. Serial No. 711,651. (No model.)

To all whom it may concern:

Be it known that I, JAMES F. DUNN, of Salt Lake City, in the county of Salt Lake and State of Utah, have invented new and useful 5 Improvements in Railway-Cars, of which the following is a full, clear, and exact description.

The purpose of this invention is to provide a construction involving a timber-cap for protecting the ends of the draft-timbers in railway-cars, by which means to prevent the timbers from being chafed and split, to which action they are especially liable during the use of the car, the invention also involving a 15 peculiar arrangement of these caps with respect to the draft-timbers and sills of the car, so that an exceedingly durable and effective structure is attained.

This specification is the disclosure of two 20 forms of the invention, while the claims define the actual scope thereof.

Reference is to be had to the accompanying drawings, forming a part of this specification, in which similar characters of reference indicate corresponding parts in all the views.

Figure 1 is a front view of the invention. Fig. 2 is a sectional view on the line 2 of Fig. 1, and Fig. 3 is a perspective view of a slightly-modified form of the invention. 30 The form of the invention shown in Figs. 1 and 2 has a cap with plane top, side, and bottom walls 4 and with a convex front wall 5, which is run into the side walls, thus avoiding short vertical edges. The cap thus constructed is fitted over the front ends of the draft-timbers 6 and secured thereto by transverse bolts 7, passing through the draft-timbers and through the side walls of the cap. The bottom wall of the cap (shown in Figs. 1 and 2) is provided with a rearward extension 8, as shown in Fig. 2, which is let into the lower face of the corresponding draft-timber 6 and through which passes a bolt 9, that also passes through the draft-timber and through 45 the sill of the car. By constructing the cap with a convex front end sharp vertical edges or corners are avoided, and the cap is thus rendered stronger and prevented from cutting and otherwise injuring objects against which 50 it may strike. The caps, with the draft-timbers, are further secured in place by means of bolts 10 and 11, the forward bolts passing through the sill and being engaged at their lower ends with a transverse bar 12, which

bears against the bottom walls of the caps, 55 and the latter bolts being passed through the sill and draft-timbers and engaged with the extremities of the bar 12. By means of the bolts 10 and 11 the bar 12 is drawn up forcibly against the bottom walls of the caps, and 60 all of the parts are thus secured in rigid connection. The parts 10 and 12 also form a means for supporting the draw-head of the car.

Fig. 3 illustrates a slightly-modified form 65 of the invention, in which the top wall of the cap is provided with an extension 8^a, similar to the extension 8 and adapted to lie on top of the draft-timber in the same manner as the extension 8 lies on the bottom thereof. 70

The timber-cap thus constructed may be produced at less cost than those now in use, and its extreme simplicity renders it durable and in every way effective.

Having thus described my invention, I 75 claim as new and desire to secure by Letters Patent—

1. A timber-cap, having plane top, bottom and side walls, a convex front wall joined to the top, bottom and side walls and running 80 into the side walls, and an extension projected out rearwardly from one wall of the cap, the cap serving to embrace the end of the timber, to protect the same from splitting and chafing.

2. A timber-cap, having top, bottom and 85 side walls, a convex front wall joined thereto and running into the side walls, and an extension projected out rearwardly from one wall of the cap.

3. In a railway-car, the combination with 90 the end sill and draft-timbers, of metallic caps fitting over the ends of the draft-timbers, the caps comprising front, side, top and bottom walls, a bolt extending horizontally through the side walls of each cap and through 95 the adjacent draft-timber, a bar bearing beneath the caps and extending transversely of the draft-timbers, bolts passed vertically through the draft-timbers and end sill and engaging the bar, and additional bolts passed 100 vertically through the bar and sill inside of the draft-timbers and respectively adjacent thereto.

JAMES F. DUNN.
